BAILER

Nelson J. White and John S. Graham,
Washington, Pa.

Application July 10, 1946, Serial No. 682,607

5 Claims. (Cl. 166—19)

1

Our invention relates to bailers that are particularly suitable for the removal of mud and sand from the bottom of the hole during the drilling of a well.

One object of our invention is to provide a bailer which can be employed in the removal of loose materials from the bottom of a well and which does not require the use of large quantities of water to render drillings or other loosened material highly fluid, as is necessary with bailers of types heretofore commonly employed.

Another object of our invention is to provide a bailer wherein there are means for operating a flap or retaining valve automatically, both in gathering a load in the bailer and in discharging the material therefrom.

One form which our invention may take is shown in the accompanying drawing wherein Figure 1 is a sectional view taken on the line I—I of Fig. 2; Fig. 2 is a rear view of the structure of Fig. 1, and Fig. 3 is a plan view of the structure of Fig. 2.

The apparatus comprises a tubular chamber 4 which may be of suitable length and diameter and which is provided with a leg 5 welded to its front wall. A flap valve 6 is pivotally connected at 7 to the rear wall of the chamber 4 and is movable from its open position to its closed position against the lower end of the chamber, as indicated by the dash lines of Fig. 1. A cross bar 8 is welded to the upper end of the chamber 4 and serves not only as a guide for a longitudinally-slidable bar 9 but as a keeper for a latch 10.

The bar 9 carries a rod 12 that is pivotally connected to the flap valve 6 so that when the bar is raised and lowered, the flap valve will be closed and opened. The latch 10 is pivotally mounted at 13 on the bar 9 and is yieldably urged in a counterclockwise direction by a spring 14 that is adjustably connected at 15 to the bar, whereby the tension of the spring may be varied. A sand line or cable 17 is connected to the upper end of the bar 9, to raise and lower the bailer.

When the parts are in the position shown in Fig. 1, the bailer can be lowered into a well. When the leg 5, which extends farther down than the gate valve 6, hits the bottom of the well or the loose material at the bottom, the downward motion of the bailer will be retarded or stopped, with consequent upward thrust on the barrel 4 relative to the bar 9, and also there will be a tendency for the bar 9 and the rod 12 to move down slightly, particularly because of the weight of the bar 9 and the rod 12. This combination of even slight forces in opposite directions upon the tube 4 and

2

the bar 9, when the leg hits bottom, results in easing or removing the weight on the lower hooked end of the latch 10 so that it will swing from beneath the bar 8, outwardly against the inner wall of the chamber 4, under the tension of the spring 14. The material to be removed from the bottom of the well will enter into the tube 4 at this time.

Thereupon vertical pull on the cable 17 will move the gate 6 to its closed position and lift the bailer from the well. At the top of the well, the material will be dumped from the bailer simply by swinging the bailer sidewise to an offside position and lowering it until its leg 5 hits the ground, the cable 17 being then slackened to let the rod 12 move down far enough to open the gate 6 for discharge of the bailer contents.

Upon swinging of the latch 10 in a clockwise direction to the position shown in Fig. 1 and placing the cable 17 under some lifting tension, the gate valve 6 will be held in its open position by the latch. The weight of the bailer chamber and its cross bar 8 upon the latch hook will provide sufficient friction to hold the latch in its retaining position, against the pull of the spring 14, while lowering the bailer into the well. When the leg 5 again hits the bottom of the well, the latch will again be released as above explained.

We claim as our invention:

- 30 1. A bailer comprising a tube that serves as a receptacle for material to be removed from a well, a flap valve pivotally connected to the lower end of the tube at one side thereof and movable into and out of position to close the lower end of the tube, a pull rod connected to a mid point on the valve and extending upwardly, a keeper carried by the tube, near the upper end thereof, a latch pivotally connected to the rod, and arranged to be moved beneath the keeper and prevent upward movement of the rod relative to the tube, a hoisting device on the upper end of the rod, a leg carried by the tube and projecting downwardly therefrom, to a plane below the lowest point reached by the flap valve during its swinging movements, and yieldable means having sufficient force to normally hold the latch away from its keeper, but of insufficient force to move the latch away from the keeper while the latch is supporting the weight of the tube.
- 35 2. A bailer comprising a tube that serves as a receptacle for material to be removed from a well, a flap valve pivotally connected to the lower end of the tube at one side thereof and movable into and out of position to close the lower end
- 40
- 45
- 50
- 55

of the tube, a pull rod connected to a mid point on the valve and extending upwardly, a keeper carried by the tube, near the upper end thereof, a latch pivotally connected to the rod, and arranged to be moved beneath the keeper and prevent upward movement of the rod relative to the tube, a hoisting device on the upper end of the rod, a leg carried by the tube and projecting downwardly therefrom, to a plane below the lowest point reached by the flap valve during its swinging movement, and yieldable means having sufficient force to normally hold the latch away from its keeper, but of insufficient force to move the latch away from the keeper while the latch is supporting the weight of the tube, the lower end of the tube being beveled and the pivotal connection of the flap valve thereto being adjacent to the uppermost point of the beveled portion.

3. A bailer comprising a tube that serves as a receptacle for material to be removed from a well, a flap valve pivotally connected to the lower end of the tube at one side thereof and movable into and out of position to close the lower end of the tube, a pull rod connected to a mid point on the valve and extending upwardly, a keeper carried by the tube, near the upper end thereof, a latch pivotally connected to the rod, and arranged to be moved beneath the keeper and prevent upward movement of the rod relative to the tube, a hoisting device on the upper end of the rod, a leg carried by the tube and projecting downwardly therefrom, to a plane below the lowest point reached by the flap valve during its swinging movement, and yieldable means having sufficient force to normally hold the latch away from its keeper when the latch is in a position where it is not supporting the weight of the tube, the leg being secured to that side of the tube which is opposite to the point at which the flap is pivotally connected thereto.

4. A bailer comprising a tube that serves as a receptacle for material to be removed from a well, a flap valve pivotally connected to the lower end of the tube at one side thereof and movable into and out of position to close the lower end of the tube, a pull rod connected to a mid point on the valve and extending upwardly, a keeper carried by the tube, near the upper end thereof,

5 a latch pivotally connected to the rod, and arranged to be moved beneath the keeper and prevent upward movement of the rod relative to the tube, a hoisting device on the upper end of the rod, a leg carried by the tube and projecting downwardly therefrom, to a plane below the lowest point reached by the flap valve during its swinging movement, and yieldable means having sufficient force to normally hold the latch away from its keeper when the latch is in a position where it is not supporting the weight of the tube, the lower end of the tube being beveled and the pivotal connection of the flap valve thereto being adjacent to the uppermost point of the beveled portion, and the leg being secured to that side of the tube which is opposite to the point at which the flap is pivotally connected thereto.

20 5. A bailer comprising a tube that serves as a receptacle for material to be removed from a well, a valve connected to the lower end of the tube and movable to open and close said end, a pull rod connected to the valve and movable upwardly relative to the tube, to close the valve, a keeper carried by the tube near the upper end thereof, a latch carried by the rod in position to move beneath the keeper to hold the rod in its lower position and to thus hold the valve open, means yieldably urging the latch to its release position, the said means being ineffective to move the latch from the keeper, while the rod is suspended from above and the weight of the tube is carried by the latch, and a stop device projecting from the lower end of the tube, in position to engage the bottom of a well and relieve the 30 latch of the weight of the tube, thereby causing the said yieldable means to move the latch clear of the keeper.
